CRANK SHAFT

Filed April 14, 1928

FIG. 1.

FIG. 2.

INVENTOR

H. R. Ricardo

9, Watson, Dart, Mass., Grindle

Atty.

UNITED STATES PATENT OFFICE.

HARRY RALPH RICARDO, OF LONDON, ENGLAND.

CRANK SHAFT.

Application filed April 14, 1928, Serial No. 270,115, and in Great Britain May 2, 1927.

This invention relates to crankshafts of the built-up type in which each crank pin is carried at its ends in holes in the adjacent pair of crank webs, a slit extending 5 outwardly from each hole through the portion of the crank web surrounding the crank pin so as to enable the web to be clamped about the end of the pin by one or more bolts or the like tending to close up 10 the slit.

In previous constructions of crankshaft of this type the slit in the crank web has extended completely through the part of the web surrounding the crank pin. With such 15 an arrangement, however, the parts of the web on either side of the slit are apt to move relatively to one another in a direction parallel to the crankshaft axis due to the stresses set up in operation, and it is the 20 object of the present invention to provide a more rigid construction in which this undesirable effect will be reduced or eliminated.

To this end, according to the present invention, the slit which enables each crank web to be clamped about the adjacent end 25 of the crank pin does not pass completely through the portion of the web surrounding the pin but a continuous bridge of metal extends across the outer end of this slit and joins the portions of the crank web on either 30 side thereof. The slit must in all cases be of sufficient length to permit the flexing of the portions of the crank web on either 35 side thereof by the bolts or the like to clamp the web about the crank pin end.

The bridge piece may extend substantially directly across the outer end of the slit but preferably in order to reduce the amount 40 of metal required on the crank web and to enable the bridge piece to be more readily flexed, the crank web is provided with a rib-like projection extending along its outer end parallel with the slit, the slit being carried 45 into this rib which thus forms a substantially U-shaped bridge piece connecting the portions of the web on each side of the slit.

Further, the outer end of the slit may be 50 enlarged to form a hole so that the complete slit may be said to have a somewhat keyhole shape, thus facilitating the drawing together about the end of the crank pin of the portions of the web on either side 55 of the slit.

Further the portion of each crank web

lying between the crank pin and the shaft is preferably reduced in width or waisted so as to render the section of the metal surrounding the pin more uniform and thus 60 enable it to be flexed more evenly to grip the pin whereby a more rigid clamping of the pin in the web is ensured.

The invention may be applied to a built-up crankshaft of various types for example 65 those in which the shaft lengths which connect adjacent cranks are either formed integral with or formed separately from and rigidly secured to the webs as by means of keys, splines or the like, but one construction 70 of crankshaft according to the present invention is illustrated by way of example in the accompanying drawings, in which

Figure 1 is an end elevation of one crank throw of a crankshaft according to this invention, the shaft itself being shown in section, and,

Figure 2 is a section on the line 2—2 of Figure 1.

In the construction illustrated the crank-shaft comprises a series of plain shaft lengths A two of which are shown. On the ends of the shaft lengths A are shrunk or otherwise rigidly secured crank webs B, a plain parallel pin C constituting a crank pin 85 being carried at its ends in holes B¹ in each adjacent pair of crank webs as shown. The crank webs B are adapted to be clamped about the ends of the crank pin C and to this end a slit or cut D is provided in each 90 web extending from the hole B¹. The portions of each web B on each side of the slit D are formed with lugs B² through which passes a bolt E provided with a nut E¹ whereby a force can be exerted tending 95 to close up the slit D and thus clamp the end of the crank pin C firmly in the web. If desired two or more bolt holes may be formed in each lug B² and a corresponding number of clamping bolts provided. The 100 slit D in each crank web B according to this invention does not extend completely through the portion of the crank web surrounding the crank pin C but is only of such length as to leave a continuous bridge 105 piece of metal extending across the outer end of the slit so as to connect the portions of the web on either side thereof. Thus the crank web is conveniently formed beyond the lugs B² on each side of the slit D with 110 a rib-like projection B³ running parallel with the slit as shown, the slit being of such

length that it extends into this rib which thus forms a substantially U-shaped bridge piece connecting the portions of the crank web on each side of the slit. The end of the 5 slit D is further conveniently enlarged as shown at D¹. The form of the bridge piece thus produced tends to give more readily when the nuts E¹ are tightened to clamp the webs about the crank pin.

10 The crank webs are preferably reduced in width or waisted as shown at B⁴ so as to render the section of the metal surrounding the crank pin C more uniform and thus enable the webs to be more evenly flexed by 15 the bolts E whereby a more rigid fixing of the crank pins in the webs tends to be effected.

The invention may be applied to built-up crankshafts either of the multi-throw or single throw type and such crankshafts may be provided with passages through which lubricating oil can be delivered to the various bearing surfaces both for the short shaft 20 lengths A between adjacent cranks and for 25 the crank pin or pins C. Thus for example when, as shown in the drawings, the short shaft lengths A are formed hollow, their ends are conveniently plugged as shown at F while oil passages G and G¹ pass from 30 the interior of these shaft lengths respectively to their bearing surfaces A¹ and to the interior of the holes B¹ in which the crank pins are mounted. Further, passages G² are provided in the crank pins themselves communicating with the oil passages G¹ and 35 adapted to deliver oil to the crank pin bearing surfaces as shown. The arrangement is conveniently such that there is a continuous oil passage extending throughout the length 40 of the crankshaft, the end shaft lengths which each carry only one crank web being provided with means respectively for delivering oil to and withdrawing it from the interior thereof so that a constant flow of 45 lubricating oil under pressure can be maintained through the crankshaft to the bearing surfaces.

It is to be understood that the details of construction may be varied considerably in 50 accordance with the requirements of the engine for which the crankshaft is intended without departing from this invention.

What I claim as my invention and desire to secure by Letters Patent is:—

55 1. A built-up crankshaft including in combination a plurality of short shaft lengths, crank webs carried by the ends of these shaft lengths and each having therein a hole adapted to receive the end of a 60 crank pin with a slit extending outwardly from this hole through the portion of the crank web around it, a bridge of metal formed integral with the crank web extending across the outer end of each slit so as 65 to join the parts of the web on either side

thereof, a crank pin having its ends disposed respectively in the holes in an adjacent pair of crank webs and means for drawing together the parts of each web on either side of the slit so as to clamp the web about the 70 end of the crank pin.

2. A built-up crankshaft including in combination a plurality of short shaft lengths, crank webs carried by the ends of these shaft lengths and each having therein 75 a hole adapted to receive the end of a crank pin with a slit extending outwardly from this hole through the portion of the crank web around it, a bridge of metal formed integral with the crank web extending 80 across the outer end of each slit so as to join the parts of the web on either side thereof, a crank pin having its ends disposed respectively in the holes in an adjacent pair of crank webs and at least one bolt serving 85 to draw together the parts of each web on either side of the slit so as to clamp the webs about the ends of the crank pin.

3. A built-up crankshaft including in combination a plurality of short shaft 90 lengths, crank webs carried by the ends of these shaft lengths and each having therein a hole adapted to receive the end of a crank pin with a slit extending outwardly from this hole through the portion of the crank 95 web around it, a curved bridge of metal formed integral with the crank web extending across the outer end of each slit so as to join the parts of the web on either side thereof, a crank pin having its ends disposed 100 respectively in the holes in an adjacent pair of crank webs and means for drawing together the parts of each web on either side of the slit so as to clamp the web about the end of the crank pin.

4. A built-up crankshaft including in combination a plurality of short shaft lengths, crank webs carried by the ends of these shaft lengths and each having therein a hole adapted to receive the end of a crank pin with a slit extending outwardly from this hole through the portion of the crank web around it, a curved bridge of metal formed integral with the crank web extending across the outer end of each slit so 115 as to join the parts of the web on either side thereof, a crank pin having its ends disposed respectively in the holes in an adjacent pair of crank webs and at least one bolt serving to draw together the parts of each web on either side of the slit so as to clamp the webs about the ends of the crank pin.

5. A built-up crankshaft including in combination a plurality of short shaft 125 lengths, crank webs carried by the ends of these shaft lengths and each having therein a hole adapted to receive the end of a crank pin with a slit extending outwardly from this hole through the portion of the crank 130

web around it, a bridge of metal formed integral with the crank web extending across the outer end of each slit so as to join the parts of the web on either side 5 thereof, a crank pin having its ends disposed respectively in the holes in an adjacent pair of crank webs and means for drawing together the parts of each web on either side of the slit so as to clamp the web 10 about the end of the crank pin, the portion of each crank web between the crank pin and the short shaft length being reduced in width as and for the purpose set forth.

6. A built-up crankshaft including in 15 combination a plurality of short shaft lengths, crank webs carried by the ends of these shaft lengths and each having therein a hole adapted to receive the end of a crank

pin with a slit extending outwardly from this hole through the portion of the crank 20 web around it, a curved bridge of metal formed integral with the crank web extending across the outer end of each slit so as to join the parts of the web on either side thereof, a crank pin having its ends disposed 25 respectively in the holes in an adjacent pair of crank webs and at least one bolt serving to draw together the parts of each web on either side of the slit so as to clamp the web about the ends of the crank pin, the portion 30 of each crank web between the crank pin and the short shaft length being reduced in width as and for the purpose set forth.

In testimony whereof I have signed my name to this specification.

HARRY RALPH RICARDO.
